CLAIM

The ornamental design for a truck tailgate fairing, as shown and described.

DESCRIPTION

FIG. 1 is a rear perspective view of the truck tailgate fairing showing my new design;

FIG. 2 is a right side elevation view thereof;

FIG. 3 is a top plan view thereof;

FIG. 4 is a front elevation view of thereof;

FIG. 5 is a rear elevation view thereof;

FIG. 6 is a left elevation view thereof; and,

FIG. 7 is a bottom plan view thereof.

The broken line showing the rear portion of a truck in FIG. 1 of the drawings is for illustrative purposes only and forms no part of the claim's design.
